UNITED STATES PATENT OFFICE.

JESSE B. STULL, OF HALFWAY, WYOMING.

TOOL.

Application filed May 5, 1920. Serial No. 379,116.

To all whom it may concern:

Be it known that I, JESSE B. STULL, a citizen of the United States, residing at Halfway, in the county of Lincoln and State 5 of Wyoming, have invented certain new and useful Improvements in Tools, of which the following is a specification.

This invention has relation to wire cutters and more particularly to a wire cutter embodied in the construction of a combination tool.

The primary object of the invention is to provide a wire cutting implement in which one of the cutting elements is of a 15 removable or replaceable character to permit the substitution of a new cutting edge for an old and worn edge.

With the above and other objects in view, the invention resides in the details of construction, combination and arrangement of parts as will be hereinafter more fully pointed out and described, reference being had to the accompanying drawings, wherein

Figure 1 is a side elevation of a tool constructed in accordance with the invention.

Figure 2 is a top plan.

Figure 3 is a sectional view taken on the line 3—3 of Figure 1.

The invention is constructed primarily of an elongated member 1 of relatively thick stock and tapering rearwardly from its most thickened portion 2 to provide a handle 3, while at its foremost end it terminates in claws 4. On one side the thickened portion 35 of the member projects upwardly above the plane of the handle 3 in arcuate curved formation to provide an offset portion 5 between the handle and the claw end 4. This offset 5 is grooved adjacent one end to provide a channel 6 opening inwardly from the handle 3 and communicating with a diagonal slot 7 opening inwardly from the opposite face of the member. Cut transversely of the lower face of the member and extending 45 across one end of the slot 7 is a recess 8 which is adapted to receive and accommodate therein the wire which is to be cut. At one side this recess is provided with a shoulder 9 and the opposite side with a vertically disposed opening 10 which is adapted to receive the supporting stud of the wire cutting block.

The wire cutting block consists of a squared head 11 of appropriate thickness 55 and provided with four sharp corners, each of which constitute a cutting edge. The

head is provided with a short cylindrical stem or stock 12 which may be inserted in the opening 10 when the cutting block is disposed in position within the recess 8. When so disposed, one side of the block lies flush against the front wall or shoulder 13 of the recess and it is moreover spaced oppositely from the shoulder 9, since both the shoulder 9 and the block are each arranged on opposite sides of the slot 7. The space provided between the rear wall 14 of the recess and the adjacent side of the block 11 constitutes the entrance or passage 15 by means of which the wire may be inserted into the slot 8, the walls of the passage thus provided maintaining the wire to be cut in a straightened and desired position.

Arranged longitudinally of the main member 1 is a lever member 16 which is provided with a handle 17 and an angularly disposed jaw 18 which is adapted to fit into the diagonal slot 7 as indicated by the dotted lines of Figure 1, this second member being pivoted as indicated at 19. The sides 80 of the lever 16 intermediate the handle 17 and the jaw 18 are beveled to provide a cutting edge which is adapted to be received in the channel 6 of the main member, the upstanding side walls of the channel embracing the cutting edge on opposite sides and being provided each with a V-shaped slot 20 adapted to coact with the V-shaped slot 21 formed in the cutting edge of the member 16 to provide a diamond shaped 90 notch into which the adjacent ends of separate wires may be inserted from opposite sides of the tool and be twisted about each other upon revolving the tool. It will thus be seen that the pivoted members cooperate 95 to provide a wire twister and to further enlarge the usefulness of the tool other additional elements such as a hammer head 22 and thread cutter 23 may be formed on the main member 1.

The gist of the invention however resides in the provision of a wire cutter formed by the jaw 18 of the member 16 and the block 11 of the main member 1. The member 16 is pivoted so that the jaw 18 moves laterally of one face of the block and this jaw is provided with a beveled cutting edge 24, so as to have a tendency to shear the wire when operating upon it. Each of the four edges of the cutting block 11 constitutes a 110 cutting edge so that when one edge has become worn or dulled a new edge may be

substituted therefor merely by punching the stem 12 out of its socket and turning the block so as to present a different corner or cutting edge. Whenever a block becomes, as a whole, useless it may be removed and an entirely new block substituted therefor.

In its modified form, the removable block 11' is provided with a beveled edge 25 which is adapted to cooperate with the adjacent beveled edge 24 of the jaw 18 in shearing the wire inserted across the recess 8. Any tendency of the block 2 to revolve about its stem 12 during the cutting action of the wire is prevented by reason of the abutment of the block with the rear shoulder 13 of the recess, which abutment insures the proper alignment of the cutting edge of the block with the jaw 18.

In using the device as a wire cutter the wire may be inserted through the recess from either side and is adapted to extend between the cutting jaws 11 and 18 which may be separated by moving handle 17 outwardly about the pivot 19. Upon moving the handles together, the wire will be caught between the beveled faces of the jaw and block respectively, and will be sheared in two as the cutting edge of the jaw passes beyond the corner or cutting edge of the block 11, the widened end of the recess permitting one of the severed ends of the wire to be carried forwardly by the advancing cutter jaw 18. The cutting operation may thus be accomplished without any undue bending of the wire while it is being operated on by the blade 18 and it is also to be noted that the passage 15 may be either increased or diminished to accommodate various sizes of wire by using large or small blocks.

From the foregoing description it will be seen that the invention thus embodies a wire cutter having a removable jaw provided with a plurality of interchangeable cutting edges which may be substituted one for the

other at the will of the person using the tool. It is also to be understood that minor changes in the details of construction, arrangement and proportionment of parts may be resorted to as fall within the scope of the invention claimed.

Having thus fully described my invention what I claim as new and desire to secure by Letters Patent is:—

A wire cutter including a main member formed from relatively thick stock and tapering rearwardly from its thickened portion to provide a handle, the foremost end of said main member projecting upwardly above the plane of the handle in arcuate curved formation to provide an offset portion, said offset portion being grooved adjacent one end to provide a channel opening inwardly from the handle and communicating with a diagonal slot opening inwardly from the opposite face of the member, the lower face of said main member being provided with a transverse recess forming a wire receiving groove, a second member pivoted to said main member and provided with a cutting end wedging into said slot, an opening formed in said main member, a square faced cutting member, a stub shaft carried by said square face member, and adapted to be received within said opening, said square face cutting member being removably disposed against one wall of the said recess with one of its faces laterally opposing the adjacent side of the cutting end of the said second member, each corner of said square member providing a cutting edge, any one of which may be brought into co-operative relation with the said cutting end.

In testimony whereof I affix my signature in presence of two witnesses.

JESSE B. STULL.
